BENCH PLANE WITH ADJUSTABLE BIT CARRIER

Charles de la Source, Paris, France, assignor to
 Les Fils de Peugeot Freres, Valentigney
 (Doubs), France, a French company

Application October 17, 1946, Serial No. 703,911
 In France December 5, 1945

2 Claims. (Cl. 145—15)

1 The invention relates to bench planes, rabbet planes and like tools used for planing wood or any other material.

One object of the invention is to provide a plane so constructed that it will be possible to adjust the width of the shaving channel or mouth without having recourse to any tool nor dismounting the iron.

According to the invention the bit carrier is resiliently pressed in an adjustable position upon the plane stock and positively held thereon, a nut or like member being used to simultaneously press the bit carrier and to hold it in position and to clamp the cam or like member used for adjusting the position of the bit carrier. Other features of the invention will appear from the following description.

In the accompanying drawing:

Fig. 1 is a longitudinal sectional view of a plane according to the invention on the line 1—1 of Fig. 3.

Fig. 2 is a transverse sectional view on the line 2—2 of Fig. 1 and

Fig. 3 is a sectional view on the line 3—3 of Fig. 1.

Referring to the drawing, 1 designates the plane stock having a U-shaped cross section and 2 denotes the plane iron or bit secured to a carrier 3 by means of a clamping plate 4, a pin 5 and a nut 6.

A cross pin 7 forming an abutment member extends horizontally between the two branches of the stock.

The bit carrier 3 is pivotally mounted on a U-shaped lever or slide comprising two lateral branches 8, 8a connected to each other at the rear by a horizontal bridge part 8b, the bit carrier being supported by two pins 9 on the branches 8, 8a.

A cam 10 provided with an inclined cam-slot 10a and an operating tongue 10b is pivotally connected by a pin 11 with the bit carrier 3. A vertical screwthreaded pin 12 is riveted to the plane stock and extends through said cam slot and through the bridge 8b of the slide 8, 8a. An operating knob or nut 13 is screwed onto the pin 12 and bears by an annular shoulder upon the upper face of bridge member 8b.

In a modification the pin 12 and nut 13 may be replaced by any other desired clamping means such as a cam.

When the nut 13 is screwed down the bit carrier 3 is pressed against the sole of the plane stock through the medium of the lever 8, 8a, said

2 lever bearing at its opposite end under the fixed pin 7.

At the same time, the nut 13 holds the cam member 10 in the angular position desired by pressing the same against the sole of the plane stock whereby the bit carrier 3 itself is surely held in position through the medium of the pivot or pin 11. When the plane is used, the axial strain due to the pressure of the work against the bit edge is thus firmly supported by the pin 12. The slide 8, 8a, 8b is made of steel and the bridge part 8b has thus a certain resiliency in a vertical direction. In this manner, the nut 13 is adapted to press downwardly upon the bridge member 8b so as to press upwardly the left hand end of the slide against the cross pin 7, while at the same time pressing the cam member 10 upon the sole of the plane stock. The bridge 8b being resilient has also for its effect to act as a nut lock for the nut 13.

In order to adjust the width 1 of the shaving channel the support 3 must be so shifted in the longitudinal direction of the stock that the cutting edge *a* will be moved towards or away from the front edge *b* of the channel. For this purpose the nut 13 is slightly unscrewed so as to partially release the tension of the lever 8, 8a whereby the pressure of the bit carrier 3 on the plane stock is just sufficient to temporarily hold the bit carrier in position.

The adjusting cam 10 is then rotated in the required direction by acting on the tongue 10b. In this movement the slotted part of the cam is shifted around the fixed pin 12 and the cam is thus displaced either forward or backward, the bit carrier 3 being carried along through the pin 11.

The adjustment obtained may be ascertained in overturning the plane and following visually the displacement of the iron edge *a* on the lower face of the sole in relation to the front edge *b* of the channel.

When the desired adjustment has been reached the nut 13 is screwed down again.

As appears from the preceding description, the adjusting operation can be made without using any tool, contrary to what may be experienced with most of the usual planes which necessitate the use of a screwdriver. Moreover the loosening of the bit carrier being effected from the rear, it is not necessary to take the iron apart, so that the adjustment of the iron proper on its carrier is not altered.

It will also be noted that the operation of the 55 adjusting cam may be effected with one hand and

it is possible to overturn the plane in the other hand and thus to follow the adjustment attentively in watching the position of the iron edge on the lower face of the plane sole.

Having now described our invention what we claim as new and desire to secure by Letters Patent is:

1. A bench plane comprising a plane stock, a bit carrier, a U-shaped resilient slide acting as a two arm lever, means for pivoting the bit carrier on the lateral parts of said slide, at an intermediate point of their length, an abutment member on the plane stock for engagement with the ends of said lateral parts, an adjusting member comprising a cam pivoted to the bit carrier and having a cam slot, a threaded pin carried by the plane stock and engaging with said cam slot, and a nut in engagement with said pin, said nut being adapted to press upon the cross part of the said slide and to clamp the cam in the adjusted position.

2. A bench plane comprising a plane stock, a bit carrier adjustably mounted on said plane stock, a resilient slide pivotally connected to said bit carrier, an abutment member carried by said plane stock and adapted to engage said slide at one end, a threaded pin secured to said plane stock and passing through said slide and a nut screwed on said pin and bearing on said slide at the other end.

10 15 20 CHARLES DE LA SOURCE.
